CLAIM

I claim the ornamental design for a lens for eyewear having a multi-colored pattern, substantially as shown and described.

DESCRIPTION

The patent or application file contains at least one drawing executed in color. Copies of this patent or patent application publication with color drawing(s) will be provided by the Office upon request and payment of the necessary fee.

FIG. 1 is a front left perspective view of the lens in its unclaimed environment of a pair of glasses in accordance with some embodiments;

FIG. 2 is a front elevation of the lens in accordance with some embodiments;

FIG. 3 is a front right perspective of the lens in accordance with some embodiments;

FIG. 4 is a front left perspective of the lens in accordance with some embodiments;

FIG. 5 is a rear elevation of the lens in accordance with some embodiments;

FIG. 6 is a rear right perspective of the lens in accordance with some embodiments; and,

FIG. 7 is a rear left perspective of the lens in accordance with some embodiments.
